UNITED STATES PATENT OFFICE.

JAMES WARES BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK.

REMOVABLE CARD FOR USE IN TIME-RECORDERS.

1,146,998.

Specification of Letters Patent.

Patented July 20, 1915.

Application filed July 19, 1911. Serial No. 639,298.

To all whom it may concern:

Be it known that I, JAMES WARES BRYCE, a citizen of the United States, and a resident of Bloomfield, in the county of Essex and State of New Jersey, have invented a new and useful Improvement in Removable Cards for Use in Time-Recorders, of which the following is a specification.

My invention relates to removable cards for use in recorders.

It has for its object to provide a card, insertible in a recorder and removable therefrom, for having records made upon it, the card capable of being easily, accurately and with certainty positioned in the recorder or brought into exact and accurate register with parts of the same. It is specially of value in cases where the same card, after having a time mark or record punched therein in a time recorder or a similar time recorder, is later inserted in the same time recorder or a similar time recorder for a subsequent time record, and where it is important or necessary to bring the previously made or punched time record or hole into exact and accurate register with a part of the time recorder with which it is to coact in the second operation, and it is of peculiar value where the previously made or punched mark or hole is a relatively small one.

My invention consists of the novel devices shown and set forth herein.

In the drawing accompanying this specification and forming part hereof, I have shown my improved card in its preferred form.

Referring to that embodiment, Figure 1 is a view of the card provided with a positioning mark or hole, and preferably with a plurality of them, and before the card has been inserted into a time recorder; Fig. 2 illustrates the same card after it has been inserted into the time recorder on the first operation and a suitable time record made thereon; the card is now ready for a subsequent insertion in the same or a similar time recorder to record the time of a second operation, or the elapsed time between the two operations; and Fig. 3 is a view of the top of the reverse side of the card.

Referring to the specific embodiment shown in the drawing, 1 is my improved card in its preferred form. It is provided with a positioning mark or hole. Prefer-

ably, I use a plurality of such marks and they are illustrated in the drawing as the positioning holes 3. These are rounded or curved in their operative parts and preferably are circular holes. They are adapted to coact with corresponding positioning devices in the time or other recorder in order to move the card into exact and accurate position in the time recorder, or into exact and accurate register with some part of the time recorder. These positioning holes are preferably made relatively large as compared with the positioning devices with which they are to coact. They or one of them is preferably placed upon the card near to that part of the card which it is desired to bring into exact register with some part of the time recorder.

In the first operation of the time recorder, holes 2, 2 are punched by suitable time recording devices, and represent the time of such operation. One of the holes 3 is preferably placed as near as possible on the card to one or more of these previously punched holes 2, as shown in Fig. 2. The positioning holes are preferably made relatively much larger than the previously punched holes. The latter are sometimes made very small, sometimes not more than mere pin-holes. Such small holes are apt not to register with their coacting device or devices in the time recorder when the card is placed in the time recorder for the second operation. This is due partly to the small size of the holes and partly to the changes in the size of the card, due to varying conditions, such as changes in temperature, humidity, etc. In practice, it has been found very difficult to register previously punched holes, especially when of a small size, with coacting devices in a time recorder, owing to variations in the conditions above referred to. This matter is so serious that sometimes it causes erroneous time records to be made on a second operation, and sometimes an absolute failure of the recording operation altogether. My improved card is designed to and does overcome these difficulties, and enables accurate and exact register to be always maintained.

In the particular form of card shown in the drawing, I have shown a space 4 for recording the time of a first or "In" operation, and in Fig. 2, the time of such operation is shown as "A. M. 12.25". I have also

provided a space 5 for a record of the time of a second or "Out" operation, and also a space 6 for a record of the elapsed time between the two operations. The card shown 5 in the drawing, Fig. 2, has been passed only through the first or "In" operation, and is in condition for the second operation. Accordingly, the "Out" time or elapsed time has not been printed in the spaces 5 and 6.

10 Fig. 3 illustrates the top of the reverse side of the card, with instructions for the workman as to the way in which the card is to be inserted. Any other suitable instructions are placed upon the card, as shown in 15 Figs. 2 and 3.

The card employed may be of any suitable shape or made of any suitable material.

20 In the drawing accompanying this specification, I have shown my improvement as embodied in a time card adapted for use in a time recorder. My invention, however, is not limited to time records or time recorders, but may be employed in any suitable recording machines adapted for the purpose.

25 What I claim as new and desire to secure by Letters Patent, is:

1. A card for use in a time recorder adapted to be inserted therein and removed therefrom, provided with a hole previously punched in the card representing the time of 30 a prior operation, and provided with a circular relatively large positioning hole placed

near the hole previously punched in the card for enabling the previously punched hole in the card to be accurately positioned 35 or registered in the time recorder.

2. A card for use in a time recorder adapted to be inserted therein and removed therefrom, provided with a hole previously punched in the card representing the time of 40 a prior operation, and provided with a plurality of relatively large circular positioning holes, one of which is located on the card near the previously punched hole for enabling the previously punched hole to be 45 accurately positioned or registered in the time recorder.

3. A card for use in a time recorder adapted to be inserted therein and removed therefrom, provided with a relatively small hole previously punched in the card representing the time of a prior operation, and provided with a positioning hole located on the card near the previously punched hole for enabling the previously punched hole to be 50 accurately positioned or registered in the time recorder.

55 In testimony whereof, I have signed my name to this specification, in the presence of two subscribing witnesses.

JAMES WARES BRYCE.
